UNITED STATES PATENT OFFICE

SAMUEL G. RUSSELL, OF KALAMAZOO, MICHIGAN, ASSIGNOR TO SHAKESPEARE COMPANY, OF KALAMAZOO, MICHIGAN

DESIGN FOR A FISHING REEL FRAME

Application filed October 14, 1931. Serial No. 41,385. Term of patent 14 years.

To all whom it may concern:

Be it known that I, SAMUEL G. RUSSELL, a citizen of the United States, residing at Kalamazoo, in the county of Kalamazoo and State of Michigan, have invented a new, original, and ornamental Design for Fishing Reel Frames, of which the following is a specification, reference being had to the accompanying drawings, forming part hereof.

Fig. 1 is a side elevation, and

Fig. 2 is an end elevation of a fishing reel frame, showing my new design.

The dominant features of my design are the end members of the frame, which are characterized by spaced, relatively narrow circular members and polygonal intermediate members of a diameter exceeding that of the circular members, the edges of the intermediate members being inwardly beveled.

I claim:

The ornamental design for a fishing reel frame, as shown and described.

SAMUEL G. RUSSELL.
